UNITED STATES PATENT OFFICE

135,118

DESIGN FOR A BANNER OR THE LIKE

Joseph J. Elsesser, Philadelphia, Pa.

Application December 24, 1942, Serial No. 109,129

Term of patent 3½ years

To all whom it may concern:

Be it known that I, Joseph J. Elsesser, residing in Philadelphia, county of Philadelphia, State of Pennsylvania, have invented a new, original, and ornamental Design for a Banner or the like, of which the following is a specification, reference being had to the accompanying drawing, forming part thereof.

In the drawing the figure represents an elevation of the banner.

I claim:

The ornamental design for a banner or the like, as shown.

JOSEPH J. ELSESSER.
